US00D751587S

(12) **United States Design Patent**
Barling et al.

(10) **Patent No.:** US D751,587 S
(45) **Date of Patent:** ** *Mar. 15, 2016

(54) **DISPLAY SCREEN WITH GRAPHICAL USER INTERFACE**

(71) Applicant: **Microsoft Corporation**, Redmond, WA (US)

(72) Inventors: **Nicholas R. Barling**, Redmond, WA (US); **Charla Pereira**, Seattle, WA (US)

(73) Assignee: **Microsoft Corporation**, Redmond, WA (US)

(*) Notice: This patent is subject to a terminal disclaimer.

(**) Term: **14 Years**

(21) Appl. No.: **29/453,565**

(22) Filed: **Apr. 30, 2013**

(51) **LOC (10) Cl.** 14-04

(52) **U.S. Cl.**

USPC **D14/486**

(58) **Field of Classification Search**

USPC D14/485-495; 715/700, 716, 730, 732, 715/752, 756, 758, 764, 769, 771, 773, 777, 715/779, 780, 809, 810, 821, 825, 833, 835, 715/838, 841, 864

(57) **CLAIM**

The ornamental design for a display screen with graphical user interface, as shown and described.

DESCRIPTION

The FIGURE is a front view of a display screen with graphical user interface showing our new design.

The broken lines shown in the drawing represent portions of the display screen with graphical user interface that form no part of the claimed design.
